UNITED STATES PATENT OFFICE

147,835

DESIGN FOR A FIGURINE OR THE LIKE

Violet Brown, Wrentham, Mass., assignor to R. M. Jordan & Company, Inc., a corporation of Rhode Island

Application September 10, 1946, Serial No. 133,216

Term of patent 7 years

(Cl. D29—23)

To all whom it may concern:

Be it known that I, Violet Brown, a citizen of the United States, residing at Wrentham, in the county of Norfolk and State of Massachusetts, have invented a new, original, and ornamental Design for a Figurine or the like, of which the following is a specification, reference being had to the accompanying drawing, constituting a part thereof.

Fig. 1 is a front elevation of a figurine showing my new design; and

Fig. 2 is a side view thereof.

I claim:

The ornamental design for a figurine or the like, substantially as shown.

VIOLET BROWN.
